Inventor
EDWIN L. CONNELL.

By ## UNITED STATES PATENT OFFICE.

EDWIN L. CONNELL, OF CLEVELAND, OHIO, ASSIGNOR TO THE VAN DORN ELECTRIC TOOL COMPANY, OF CLEVELAND, OHIO, A CORPORATION OF OHIO.

ELECTRIC SWITCH AND HANDLE.

Application filed August 11, 1921. Serial No. 491,629.

To all whom it may concern:

Be it known that EDWIN L. CONNELL, a citizen of the United States of America, residing at Cleveland, in the county of Cuyahoga and State of Ohio, has invented certain new and useful Improvements in Electric Switches and Handles, of which the following is a specification.

My invention relates to improvements in electric switch and handle of the type adapted for employment with manually controlled electric tools, and has for its object the provision of a simple and compact construction adapted for the convenient handling of the electric tool and for its automatic control.

It is highly desirable, if not necessary in the employment of electric tools, that the power shall be instantly, positively and automatically cut off, either at the will of the operative upon releasing the controlling member, or upon its accidental release.

With a switching handle of this type, it also is desirable that it shall be positioned close to the tool, yet it must be so disposed as to be out of the way and permit the use of the tool at close quarters.

My invention has proceeded with these features in view, and the present improvements embody a switching handle and switch disposed rearwardly of the tool and slightly at one side; the switch being of a preferred automatically-opening type, which is compactly mounted in a hollow section of the handle closely adjacent to the controlled tool or implement.

My improvements may be more readily explained by making reference to the accompanying drawings, wherein:

Figure 1 is a view in elevation, and partially sectioned, illustrating an electrically-actuated drill equipped with my improvements.

Fig. 2 is an enlarged fragmentary view in vertical section, better illustrating the switch and handle construction, and

Fig. 3 is an enlarged horizontal section taken on line 3—3, Fig. 2.

Throughout the several figures of the drawings I have employed the same character of reference to indicate similar parts.

Upon referring to Fig. 1, it will be seen that the rearwardly positioned handle portion lies within the contour of the associated electric drill, except upon one side,

whereon a casing is provided for the switch proper and for bringing in the electric power connection.

The drill *a* may be taken as typical of various electric tools adapted for manual control. At the rear or left of the drill there is provided a removable casing section *c*, secured in place by screws *b*. This member preferably has an integral pistol-grip handle *d* having a gripping portion and a switch-containing chamber *d'*. The latter is closed by an insulating base plate *d''*, to which the connecting wires *e*, *e'* of the power circuit are attached.

The controlling switch, as best shown in Fig. 2, comprises a pivoted switch lever *f* mounting a circuit-closing member *f'* which is adapted to engage contacts *g*, *g'*, and complete the gap in the circuit. The switch lever *f* is bifurcated and accommodates the controlling cam *h* which is mounted upon a common pivot pin *i*. This cam has two operative faces *h'*; *h''*, alternatively engaging the spring-pressed roller *f''*. When said roller is in contact with the upper face *h'* of said cam, the switch lever is held in its open position against the stop *j*. Upon partially rotating the cam in a clockwise direction, or to the dotted line position, the roller will snap past the point of the cam and, riding the under face *h''* of said cam, will force the switch lever down to close the circuit between the contacts *g*, *g'*, as also shown by dotted lines. A stop *j'* also is provided for the cam.

In order to control said switch both manually and automatically, a lever member or trigger *k* is pivoted at *k'* within the handle and normally is maintained in its outward or full line position by the spring *k''*. The shorter end of the trigger *k* is connected with the cam *h* by the link *l*, so that the cam normally is maintained in its full line position by the tension of spring *k''*, acting through the trigger *k* and link *l*. This insures the maintenance of an open circuit through the switch at all times that the trigger is not retracted.

When the operative has placed the drill in its desired position, he merely closes his fingers upon the trigger and gripping portion of the tool handle, and thereby immediately actuates the cam, as above explained, to close the power circuit through the tool, and its motor is energized to rotate the drill

as long as the switch is thus held closed. Immediately upon the intentional or accidental release of the trigger *k*, however, the spring *k''* reacts upon the cam to rotate it 5 to the full line position, and the spring-pressed roller *f''* rides the upper face *h'* of said cam, and almost instantly opens the circuit to the motor. Not only does this afford the most effective and prompt control of the tool, but, in addition, the apparatus is safeguarded against accident.

It will be appreciated that the controlling switch and containing handle are relatively simple and are extremely convenient and 15 effective in use. Thus, it is seen that the handle is most efficiently positioned approximately in the axis of the tool and rearwardly thereof, or in line with drill so that it may best be directed by the operative. The 20 switch is disposed closely adjacent to but outside of the gripping portion of said handle and the controlled motor of the tool, but at one side of the structure; the other side of the structure being substantially flush 25 and unbroken, so that the drill may be used in corners and angular structures without difficulty.

Having now described the preferred embodiment of my invention, I claim as new 30 and desire to secure by Letters Patent, both

in specific and equivalent forms, the following:

1. In apparatus of the class described, the combination with a handle member, of an associated trigger, a normally tensioned 35 spring, and a controlled switch comprising a cam actuated by the trigger and spring, a switch arm and its coacting contact, and means reacting upon the cam for opening and closing the circuit between the switch 40 arm and contact alternatively with the operative position of the cam, substantially as set forth.

2. In apparatus of the class described, the combination with a pistol grip handle, of 45 a trigger pivoted upon said handle, an associated spring therefor, and switching mechanism controlled by the trigger and spring, comprising a pivoted switch arm, its coacting contacts, an actuating cam for said lever, a spring pressed roller engaging alternative faces of said cam, whereby the switch arm is maintained either in its open or closed position, and means connecting said trigger and cam, substantially as set 50 forth.

In testimony whereof I do now affix my signature.

EDWIN L. CONNELL.
